UNITED STATES PATENT OFFICE.

ANTHONY KOLKIEWICZ AND MAURICE M. WEINSTEIN, OF DETROIT, MICHIGAN.

SPREADING AND LOCKING DEVICE.

1,287,048.

Specification of Letters Patent. Patented Dec. 10, 1918.

Application filed July 17, 1918. Serial No. 245,354.

To all whom it may concern:

Be it known that we, ANTHONY KOLKIEWICZ, and MAURICE M. WEINSTEIN, citizens of the United States of America, residing at Detroit, in the county of Wayne and State of Michigan, have invented certain new and useful Improvements in Spreading and Locking Devices, of which the following is a specification, reference being had therein to the accompanying drawings.

This invention relates to a spreading device for exerting pressure in opposite directions upon opposed members and for locking the same in adjusted position, said device being particularly adapted for locking the leveling pins of a drag supporting table of a molding machine, and its object is to provide means whereby the spreading or expanding operation and the locking of the parts in expanded position are accomplished by the operation of a single lever, and further to provide a construction whereby the four pins of a drag table are engaged with an even pressure to effectually lock them in the position to which they are adjusted by being brought into contact with the bottom board of a flask. A further object is to provide certain other new and useful features in the construction and arrangement of parts, the invention consisting in the matters hereinafter more fully described and particularly set forth in the appended claims, reference being had to the accompanying drawing in which:—

Figure 1 is a plan view of the drag supporting table of a molding machine illustrating an application of the invention thereto;

Fig. 2, a side elevation of the table and a flask of a molding machine with the locking device shown in elevation upon the table; and

Fig. 3, is a perspective detail of a pair of locking arms.

Obviously, the invention may be applied to any machine or structure where it is desired to create pressure between two members tending to spread them apart, and to hold them in separated relation, but as a use to which the invention is particularly adapted it is shown as applied to the drag supporting table 1 of a molding machine, which table is provided in the usual manner, with four pins 2 extending through the table near each corner thereof. These pins are free to slide in sleeves 3 fixed in the

table, and the lower ends of the pins are reduced in diameter to form a shoulder on each, which shoulder is engaged by a coiled spring 4 sleeved on the end portion of the pin between said shoulder and the lower end of the sleeve to normally hold the pin projected from the upper end of the sleeve to the full limit allowed by a cotter pin or stop 5 passing through the pin to engage the lower end of the sleeve and limit the upward projection of the pin by the spring. The table 1 may be supported in any convenient manner, as by a tubular pedestal 6 forming a guide for a post 7 attached to the lower side of the table, so that the table may be raised or lowered by the operator to bring the leveling pins 2 into engagement with the bottom board 8 of a flask 9 which may be of any well known form and construction and may be supported by hangers 10 engaging trunnions 11 on the ends of the flask, in the usual manner. Should the bottom board 8 not be exactly parallel with the face of the table, the pins coming in contact therewith will yield slightly to compensate for such irregularity, and if, after these pins have adjusted themselves to the board, if they are locked in such position, then, after the clamp indicated at 12 is removed to release the bottom board from the flask, the table 1 may be lowered and the drag of the mold resting thereon will also be lowered, drawing out of the flask.

If the bottom board was not supported on the table in the exact position in which it is held relative to the flask when in place thereon, the drag would not draw evenly and would become broken, and therefore the leveling pins are employed to take care of any inequality and are locked after being brought into contact with the bottom board to hold the pins depressed against the action of their springs 4.

To so lock the pins 2, locking arms 13 are provided to engage the sides of the pins within notches 14 cut in the sleeves 3 at the upper side of the table, said arms having concaved end faces 15 to engage the pins, and these arms extend radially inward toward the center of the table, there being a pair of arms for the two pins at each end of the table, which pairs of arms having inner end portions 16, each bent laterally toward the other arm of the pair with these end portions reduced in thickness and overlapped, as shown in Fig. 3, there being a shoulder

17 formed on each arm or bar 13 to be engaged by the overlapped end portion 16 of the other arm of the pair. The arms of each pair are thus independently adjustable 5 to provide for variations in distances between the pins of each pair and also to equalize the pressure on the pins when force is applied against these overlapped ends to move the arms outwardly and bring their 10 outer ends into firm frictional contact with the sides of the pins 2, to lock the same in their sleeves.

To move one pair of arms in one direction, and the other pair in an opposite direction, 15 means is interposed between the two pairs of arms to engage their overlapped ends, consisting of a toothed gear 18 pivotally secured upon the face of the table 1 midway between the pairs of overlapped ends of the arms, by 20 a pivot pin 19 secured in an opening in the table, and interposed between this gear and the overlapped ends of the bars 13, are wedge-shaped rack-bars 20, said rack bars being each of a greater width at one end 25 than at the other end, arranged with their like ends extending in opposite directions so that when the gear is turned in one direction by means of a handle 21 thereon, these wedges will be moved endwise to both exert 30 a wedging action between the gear and the overlapped ends of the locking bars 13. A reverse turning movement of the gear will withdraw both wedges and release the bars so that the pins 2 will be free to be moved 35 in their sleeves by the springs 4. The operating handle 21 is formed integral with a circular flange plate or disk 22 which is rigidly secured to the upper end of the gear so that this plate will overlie the wedge 40 racks 20 at its edges and form a guide therefor to retain them in engagement with the gear.

By providing teeth on the wedges 20 to be engaged by the gear, these wedges are 45 positively forced endwise and a high leverage is secured which will drive the wedges in between the gear and locking bars with ample force to securely lock the pins, without great effort on the part of the operator, 50 and when these wedges are so driven in, they lock the bars in contact with the pins without liability of accidental release due to such wedging action.

As each locking bar 13 for each pin is independent of its companion bar, and as the wedges engage the overlapping ends of each pair of bars, force will be applied equally to the two pins locked by a pair of the bars, and further independent adjustment of the 60 bars or arms is provided for.

Obviously, changes may be made in the form, construction and arrangement of locking bars, wedges and gear and in the size and proportion of the parts, within the 65 scope of the appended claims and we do not

therefore limit ourselves to the particular structure shown.

What we claim is:—

1. The combination with a table and pins movable in openings in the table, of locking means having opposed members to engage the pins, a rotatable member arranged between said opposed members, and wedge members interposed between said rotatable member and said opposed members and moved longitudinally by a turning movement of said rotatable member. 70

2. In a molding machine, the combination with a table and pins movable in openings in the table, said pins being arranged at the four angles described by a rectangular figure, of inwardly converging locking bars to engage the pins, a rotatable gear arranged between opposed ends of the bars, and wedge-shaped rack-bars interposed between said gear and the bars in engagement with said gear. 80 85

3. The combination with a table and pins movable in openings in the table, said pins being arranged at the four angles described by a rectangular figure, of locking bars to engage said pins at one end and converging inwardly, a pivoted tooth gear arranged between opposed end portions of the bars, means for turning the gear, wedges engaging the opposed end portions of the bars and having teeth engaging the gear. 90 95

4. In a device of the character described, the combination of locking members arranged in pairs with the adjacent ends of the members of each pair oppositely bent and overlapped, and means interposed between the overlapped ends of one pair of locking members and the overlapped ends of the other pair of members to move the pairs of members in opposite directions. 100 105

5. In a device of the character described, the combination of locking members arranged in pairs with the adjacent ends of the members of each pair oppositely bent and overlapped, a wedge member interposed between the overlapped ends of one pair of locking members and the overlapping end of the other pair, and manually operable means for moving said wedge member to spread the pairs of members apart. 110 115

6. The combination with a table and pins movable in openings in the table, said pins being arranged at the four angles described by a rectangular figure, of locking bars to engage said pins at one end and converging inwardly, the bars being arranged in pairs with the inner ends of each pair bent in opposite directions and overlapped, and means between the overlapped ends of one pair and the overlapped ends of the other pair, adapted to engage the same and move the pairs of bars in opposite directions to engage their ends with said pins. 120 125

7. The combination with a table and pins 130

movable in openings in the table, said pins being arranged at the four angles described by a rectangular figure, of locking bars to engage said pins at one end and converging inwardly, the bars being arranged in pairs with the inner ends of each pair bent in opposite directions and overlapped, wedging means interposed between the overlapped ends of one pair and the overlapped ends of 10 the other pair to move the pairs in opposite directions, and manually operable means for moving said wedging means.

8. The combination with a table and pins movable in openings in the table, said pins being arranged at the four angles described by a rectangular figure, of locking bars to engage said pins at one end and converging inwardly, the bars being arranged in pairs with the inner ends of each pair bent in opposite directions and overlapped, a rotatable member pivoted upon said table, and wedge members interposed between said ro-

tatable member and the overlapped ends of each pair of bars.

9. The combination with a table and pins 25 movable in openings in the table, said pins being arranged at the four angles described by a rectangular figure, of locking bars to engage said pins at one end and converging inwardly, the bars being arranged in pairs 30 with the inner ends of each pair bent in opposite directions and overlapped, a gear pivotally attached to the table, a handle for operating the gear, and a wedge shaped rack-bar at each side of said gear between it 35 and the overlapped ends of the pairs of bars.

In testimony whereof we affix our signatures in presence of two witnesses.
